UNITED STATES PATENT OFFICE.

HARRY THAYER KINGSBURY, OF KEENE, NEW HAMPSHIRE.

DESIGN FOR A TOY HOE AND RAKE.

SPECIFICATION forming part of Design No. 35,444, dated December 17, 1901.

Application filed November 8, 1901. Serial No. 81,632. Term of patent 14 years.

To all whom it may concern:

Be it known that I, HARRY THAYER KINGSBURY, a citizen of the United States, residing at Keene, in the county of Cheshire, State of New Hampshire, have invented a certain new and original Design for a Toy Hoe and Rake, of which the following is a description, reference being had to the accompanying drawings, and to the letters of reference marked thereon.

My invention relates to a design for a toy hoe and rake; and it consists in the shape and configuration hereinafter described, and illustrated in the accompanying drawings, in which—

Figure 1 represents a front perspective view of the hoe and rake, and Fig. 2 a rear perspective view of the same.

In the drawings, A represents the tool as a whole, the lower part of which is squared across its lower surface and is provided with

a narrowed or neck portion B, which merges into the rake portion C. The interior is cut away between the portions A and C to form the projecting arms D. Ribs E are provided along the edges of the neck portion B, which ribs are curved at their lower ends and extend into the body of the hoe portion A.

The leading feature of the design consists in a toy hoe and rake of the shape and configuration herein shown.

Having thus described my invention, what I claim as new, and desire to secure by Letters Patent, is—

The design for a toy hoe and rake, substantially as shown and described.

In testimony whereof I affix my signature in presence of two witnesses.

HARRY THAYER KINGSBURY.
